APPARATUS FOR STENCILING ARTICLES

Dietrich G. Rempel, Barberton, Ohio, assignor
to The Sun Rubber Company, Barberton, Ohio,
a corporation of Ohio

Application April 17, 1940, Serial No. 330,100

9 Claims. (Cl. 101—114)

This invention relates to apparatus for stenciling articles, such as toys, rubber character dolls, balls, or the like, and in particular, relates to apparatus for stenciling such articles with paint spray. The present application is an improvement on application, Serial No. 280,979, filed June 24, 1939.

A purpose of this invention is to provide apparatus of the character described which is simple and compact, and which requires a relatively small degree of skill to operate.

Another purpose of the invention is to provide such apparatus in which is minimized the damage caused by smearing or marking the articles in positioning the same in or removing them from the stenciling mask.

These and other objects of the invention will be manifest from the following brief description and the accompanying drawing.

Of the accompanying drawing:

Figure 1 is a front elevation of the stenciling apparatus embodying the invention.

Figure 2 is a cross-section taken on line 2—2 of Figure 1.

Figure 3 is a cross-section taken on line 3—3 of Figures 1 and 4.

Figure 4 is a cross-section taken on line 4—4 of Figure 3.

Figure 5 is a cross-section taken on line 5—5 of Figure 3.

Referring to the drawing, the numeral 10 designates a post or support secured in upright position on a table or work bench 11, as by means of a clamping device 12 fixed on the lower end of said post. Journalled in the upper end of post 10, to rotate on a horizontal axis, may be a shaft 13 which carries sectional stenciling mask units, indicated generally at 14.

The unit 14 may comprise a pair of relatively movable registering mask sections 15 and 16, having secured thereto arms 17 and 18, adapted to be removably and replaceably received in sockets 19 and 20 of a pair of relatively movable supporting members 21 and 22, respectively, said arms 17 and 18 being held in fixed relation in said sockets by means of thumb screws 23, 23. The supporting member 21 may be fixedly mounted on a fluid-pressure operated cylinder 24 carried by rotatable shaft 13, said cylinder being arranged with the longitudinal axis thereof transversely of the axis of the shaft 13. Extending from one end of the cylinder 24 may be a piston rod 25 of a piston 25^a, the outer end of which rod is connected to an outwardly extending angular portion 26 of supporting member 22. A rod 28

fixed at one end to the extension 26 of member 22 extends in parallel with the axis of cylinder 24, as guided by being slidably received in a sleeve 29 fixed on the cylinder 24, whereby the rod 28 will prevent relative rotation of the member 22 about the axis of the cylinder in all radially adjusted positions of member 22 toward and from the relatively fixed member 21. The various parts of the unit 14 are arranged so that the mask sections 15 and 16 will rotate in substantially balanced condition about the axis of the shaft 13 when said mask sections are in registering relation. A reduced extension 31 may be provided on shaft 13 at the side of the post 10 opposite from the mask unit 14, to which extension is secured a crank handle 32 for manually rotating the shaft 13 carrying the mask unit 14.

For operating the fluid-pressure cylinder 24 to move the mask section 16 from and toward mask section 15, conduits 33 and 34 secured to the cylinder may extend from opposite ends thereof to communicate with passages 35 and 36 formed in the shaft 13, which in turn communicates with a pair of annular grooves 37 and 38, respectively, in shaft 13, these grooves being closed to the exterior by the bearing surface in post 10 for shaft 13. Arranged in the post 10 to communicate with the grooves 37 and 38 in all rotated positions of the shaft 13, may be passages 39 and 40, respectively, which extend downwardly to the inner end of a bore 41 in the rear face of the post 10. Mounted in the bore 41 may be a rotatable disc 42, having openings 43 and 44 arranged to communicate with the passages 39 and 40, respectively, by rotation of the disc 42, the arrangement being such that the disc may be rotated in one direction or the other to communicate either the passage 39 or the passage 40 with a chamber 41^a located between the outer face of the disc 42 and a plug 45 threaded in the bore 41. The chamber 41^a may connect with a suitable source of fluid-pressure supply (not shown), through a suitable conduit 46 (see Figure 3). For rotating the disc 42 to control cylinder 24, a pin 47 integral with the disc is rotatably received forwardly through the post 10 and has fixed on the outer end thereof a control lever 48. Spaced stop-pins 49, 49 are provided on the front face of post 10 to be engaged by the lever for limiting the rotation of disc 42 between the positions in which a chamber 41^a communicates either with passage 39, through the opening 43 in the disc, or with the passage 40, through the opening 44 in the disc, to supply fluid-pressure to one end or the other of cylinder 24, as desired.

for opening or closing the mask sections 15 and 16, in any rotated position of the unit 14. On the inner face of the disc 42 may be an arcuate groove 50 for communicating one or the other of the passages 39 and 40 with an exhaust passage extending through the post 10 to the front face thereof. The arrangement is such that when the lever 48 is in the full-line position shown in Figures 1 and 4, fluid-pressure from conduit 46 will pass through opening 43 in disc 42, communicating through passage 39 with grooves 37 in the shaft 13, and thence, through passage 36 and conduit 34, with the outer end of cylinder 24 to urge the piston 25^a thereof inwardly, thereby maintaining the mask sections in closed registering relation, as shown in Figure 1. The other end of the cylinder is at the same time exhausted through conduit 33, passage 35 and annular groove 38 in shaft 13, passage 40 in the post, arcuate groove 50 in disc 42, and thence through the outlet 51 to the atmosphere. Conversely, for opening the mask sections, lever 48 is moved to the chain-dotted position shown in Figures 1 and 4, thereby to communicate the inner end of cylinder 24 with the source of fluid-pressure supply through conduit 33, passage 35 in the shaft 13, annular groove 38, passage 40 in the post, opening 34 in the disc 32, the outer end of the cylinder then being exhausted through the other connecting passages communicating with arcuate groove 50, and outlet 51, whereby piston 25^a is actuated to move the mask sections 15 and 16 apart radially of the axis of rotation of the unit.

In the operation of the apparatus the operator, by means of a handle 32, rotates the unit 14 to the position thereof shown in Figure 1, and then moves the lever 48 to the chain-dotted position thereof shown in Figures 1 and 4, thereby actuating the cylinder 24 to move the mask section 16 to the chain-dotted position shown in Figure 1, in which position an article A may be inserted in the cavity of the lower mask section 15. When the article is in position, the operator may then shift the lever 48 back to the full-line position shown in Figures 1 and 4, thereby actuating the cylinder as described to move the mask section 16 toward registering relation with the mask section 15 about the article A, as shown in full-lines in Figure 1. The parallel movement of the section 16 radially of the axis of rotation of the unit will minimize frictional engagement with the article during the closing movements of said mask section, thereby materially reducing the danger of smearing the freshly painted article.

When the articles are positioned in the mask unit, the operator then turns the crank 32 with one hand to rotate the mask unit 14, the other hand being used to handle a spray gun of known type for applying paint spray through the openings 14^a, 14^b in the mask sections.

The apparatus shown and described is simple to operate, the operator using one hand to manipulate the spray gun (not shown), while the other hand is used to operate lever 48 for moving the mask sections from and toward each other. Thus one hand may be kept relatively clean for positioning the articles in and removing them from the mask sections, it being unnecessary for the operator to handle the mask sections, which are usually coated with lubricating materials to permit ready removal of paint spray from the outer surfaces thereof.

It is understood that a number of units 14

may be located at a plurality of stations for performing various coloring operations on character dolls, for example.

Modifications of the invention may be resorted to without departing from the spirit thereof or the scope of the appended claims.

What is claimed is:

1. Apparatus for stenciling articles comprising a unit rotatable about an axis, said unit including a pair of stenciling mask sections, means for mounting said mask sections to be relatively shiftable from and toward each other in parallelism substantially radially of said axis, means for rotating said unit about said axis, and means operable at will for shifting said mask sections toward and from each other, said unit thereby being rotatable about said axis to expose various openings in the mask sections for reception of a spray of paint or the like onto an article received between said sections.

2. Apparatus for stenciling articles comprising a unit rotatable about a substantially horizontal axis, said unit including a pair of stenciling mask sections, means for mounting said mask sections to be relatively shiftable from and toward each other substantially radially of said axis in parallelism, means for rotating said unit about said axis, and means operable at will for shifting said mask sections toward and from each other in parallelism, said unit thereby being rotatable about said axis to expose various openings in the mask sections for reception of a spray of paint or the like onto an article received between said sections.

3. Apparatus for stenciling articles comprising a support, a unit mounted on said support to rotate about a horizontal axis, means operable for rotating said unit, said unit including a pair of mask sections shiftable from and toward each other radially of said axis, and power means carried by said rotatable unit operable at will to shift said mask sections toward and from registering relation about an article received between the same, said unit being rotatable to expose various openings in the mask sections for reception of a spray of paint or the like onto an article received between said sections.

4. Apparatus for stenciling articles comprising a support, a unit mounted on said support to rotate about a substantially horizontal axis, means for rotating said unit about said axis, said unit including a pair of mask sections shiftable from and toward each other radially of said axis, and power means carried by said rotatable unit operable to shift said mask sections in parallelism toward and from registering relation about an article received between the same, said unit being rotatable to expose various openings in the mask sections for reception of a spray of paint or the like onto an article received between said sections.

5. Apparatus for stenciling articles comprising a support, a unit rotatably mounted on said support to rotate about a substantially horizontal axis, means for rotating said unit about said axis, said unit including a pair of mask sections shiftable from and toward each other radially of said axis, means carried by said rotatable unit operable at will to shift said mask sections toward and from registering relation about an article received between the same, and cooperating means on said rotatable unit and said support for operating said shifting means, said unit being rotatable to expose various openings in the mask sections for reception of a spray of paint or the

like onto an article received between said sections.

6. Apparatus for stenciling articles comprising a support, a unit mounted on said support to rotate about a substantially horizontal axis, means for rotating said unit about said axis, said unit including a pair of relatively shiftable mask sections, means carried by said rotatable unit operable to shift said mask sections in parallelism toward and from registering relation about an article received between the same, and cooperating means on said rotatable unit and said support for operating said shifting means, said unit being rotatable to expose various openings in the mask sections for reception of a spray of paint or the like onto an article received between said sections.

7. Apparatus for stenciling articles comprising a relatively fixed support, a unit rotatably mounted on said support at one side of the support, said unit including a pair of relatively shiftable registering mask sections, means for rotating said unit on said support, means carried by said rotatable unit for shifting said mask sections toward and from registering relation about 25 an article to be stenciled, and cooperating means

on said rotatable unit and said relatively fixed support for operating said shifting means.

8. Apparatus for stenciling articles comprising a relatively fixed support, a unit rotatably mounted on said support at one side thereof, said unit including a pair of relatively shiftable registering mask sections, means for rotating said unit on said support, fluid-pressure means carried by said rotatable unit for shifting said mask sections in parallelism toward and from registering relation about an article to be stenciled, and cooperating means on said rotatable unit and said support connected to a source of fluid pressure for operating said shifting means.

10 15 9. Apparatus for stenciling articles comprising a support, a unit mounted in said support to rotate about a substantially horizontal axis, said unit including a pair of relatively shiftable registering mask sections, means for rotating said unit on said support, and means rotatable with said rotatable unit and operable at will for shifting said mask sections in parallelism radially of said horizontal axis toward and from registering relation about an article to be stenciled.
